UNITED STATES PATENT OFFICE

159,401

COMBINATION GIRDLE AND PANTY

Lester Zimmerman, New York, N. Y.

Application November 26, 1948, Serial No. 149,840

Term of patent 3½ years

(Cl. D20—2)

To all whom it may concern:

Be it known that I, Lester Zimmerman, a citizen of the United States, and a resident of the county, city, and State of New York, have invented a new, original, and ornamental Design for a Combination Girdle and Panty, of which the following is a specification, reference being had to the accompanying drawing, constituting a part thereof in which:

Fig. 1 is a front perspective view of my combination girdle and panty forming the subject matter of my invention.

Fig. 2 is a rear perspective view of the same.

The characteristic feature of my design resides in the combination on the paneled girdle disclosed of the high curved lower front section extending well above the crotch portion and the attached panty having well defined inner leg portions, said panty member being constantly visible through the curved opening as shown.

I claim:

The ornamental design for a combination girdle and panty, substantially as shown and described.

LESTER ZIMMERMAN.
